(57) **CLAIM**

The ornamental design for a dust separator as shown and described.

DESCRIPTION

FIG. 1 is a front, side, and top perspective view of a dust separator in a state of use according to an embodiment; FIG. 2 is a front perspective view of the dust separator of FIG. 1;

FIG. 3 is a section view of the dust separator taken along section line 3-3 in FIG. 1; and,

FIG. 4 is a bottom view of the dust separator of FIG. 1.
